UNITED STATES PATENT OFFICE.

ERNEST FRANCIS EISINGER, OF NEW YORK, N. Y., ASSIGNOR TO LA FRANCE NOVELTY CO., OF NEW YORK, N. Y., A CORPORATION OF NEW YORK.

DESIGN FOR A TEXTILE TRIMMING.

51,229.

Specification for Design.

Patented Sept. 4, 1917.

Application filed May 14, 1917. Serial No. 168,616. Term of patent 3½ years.

To all whom it may concern:

Be it known that I, ERNEST FRANCIS EISINGER, a citizen of the United States, residing in the city of New York, borough of the Bronx, in the county of Bronx and State of New York, have invented a new, original, and ornamental Design for a Textile Trimming, of which the following is a specification, reference being had to the accompanying drawing, forming a part thereof.

The figure is a plan view of a portion of a textile trimming illustrating my new design.

I claim:

The ornamental design for a textile trimming as shown.

ERNEST FRANCIS EISINGER.
